UNITED STATES PATENT OFFICE.

MORRIS JACOBS, OF SACRAMENTO, CALIFORNIA.

SHAVING-BRUSH.

1,074,324.

Specification of Letters Patent.

Patented Sept. 30, 1913.

Application filed December 20, 1912. Serial No. 737,899.

To all whom it may concern:

Be it known that I, MORRIS JACOBS, a citizen of the United States, residing at Sacramento, in the county of Sacramento and State of California, have invented new and useful Improvements in Shaving-Brushes, of which the following is a specification.

The invention relates to brushes, and more particularly to the class of shaving brushes.

The primary object of the invention is the provision of a brush wherein liquid soap may be contained within the stock thereof so that it will be fed therefrom to the bristles for the application of the soap to the face of a user, whereby lather can be formed, thus obviating the necessity of the use of an ordinary shaving mug, cake or stick shaving soap.

Another object of the invention is the provision of a brush of this character in which the parts thereof can be readily and easily disassembled so as to permit the thorough cleaning thereof, thus rendering the brush sanitary.

A still further object of the invention is the provision of a brush of this character in which the liquid soap can be readily and easily applied to the face of the user on the rubbing of the brush or the manipulation thereof by the said user.

A still further object of the invention is the provision of a shaving brush of this character which is extremely simple in construction, thoroughly reliable and efficient in its purpose, and inexpensive in manufacture.

With these and other objects in view the invention consists in the construction, combination and arrangement of parts as will be hereinafter more fully described, illustrated in the accompanying drawings forming a part of the specification, and pointed out in the claim hereunto appended.

In the drawings: Figure 1 is a side elevation of a brush constructed in accordance with the invention. Fig. 2 is a vertical longitudinal sectional view thereof. Fig. 3 is a side elevation of the funnel-shaped feed tube removed from the brush, and being partly in section.

Similar reference characters indicate corresponding parts throughout the several views of the drawings.

Referring to the drawings by numerals 55 the brush comprises a cylindrical hollow stock or body 5, preferably constructed from vulcanized rubber, although it may be made from hardwood or any other suitable material, having fixed at one end a clamping 60 ring 6 in which are secured the bristles 7 in the usual well-known manner, while the opposite end is formed with a reduced threaded neck 8, on which is detachably engaged the internal threaded collar 9 of a rubber spherical shaped bulb 10, the stock or body 5 being provided with an internal cavity 11 accessible through the reduced threaded open neck 8 on the detachment of the bulb therefrom.

Removably held within the cavity 11 is a funnel-shaped feed tube 12 preferably constructed from glass, the tapering discharge end 13 of which is passed through a central opening 14 establishing communication between the discharge end 13 and the bristles or hairs 7 so that liquid soap contained within the bulb 10 can be forced through the tube 12 into the said bristles or hairs, whereby on rubbing the latter upon the face 80 of the user the soap will be applied thereto for producing lather, the brush being manipulated in the ordinary well-known manner over the face of the user. The bulb 10 is removed and filled with liquid soap, and 85 thereafter the neck 8 is engaged with the same so that on compressing the said bulb 10 the liquid soap will flow through the feed tube 12 into the bristles or hairs as will be clearly apparent. The cavity 11 is correspondingly shaped with respect to the feed tube 12 and serves as a seat therefor interiorly of the stock 5 of the brush.

From the foregoing it is thought that the construction and manner of operation of 95 the device will be clearly understood, and therefore a more extended explanation has been omitted.

What is claimed is:

A brush comprising a stock having a 100 socket, in one end, bristles fixed in the said socket, the said stock being further pro-

vided with an inwardly tapered cavity opening through its opposite end and also opening into the socket centrally thereof, a feed tube correspondingly shaped to the said cavity and removably held therein and having a discharge tip projecting into the socket, a collar threaded in the larger end of the said cavity for holding the feed tube against displacement therein, and a com-

pressible bulb having a neck fixed in the 10
collar.

In testimony whereof I affix my signature
in presence of two witnesses.

MORRIS JACOBS.

Witnesses:
